(57) **CLAIM**
The ornamental design for a toy weapon, as shown and described.

DESCRIPTION

FIG. 1 is a perspective view of a toy weapon;
FIG. 2 is another perspective view thereof;
FIG. 3 is a front view thereof;
FIG. 4 is a rear view thereof;
FIG. 5 is a top view thereof;
FIG. 6 is a bottom view thereof;
FIG. 7 is a right side view thereof;
FIG. 8 is a left side view thereof;
FIG. 9 is a front view in a transformed state thereof;
FIG. 10 is a right side view in a transformed state thereof;
FIG. 11 is a left side view in a transformed state thereof;
FIG. 12 is a perspective view for the gun form thereof;
FIG. 13 is another perspective view of the gun form thereof;
FIG. 14 is a front view of the gun form thereof;
FIG. 15 is a rear view of the gun form thereof;
FIG. 16 is a top view of the gun form thereof;
FIG. 17 is a bottom view of the gun form thereof;
FIG. 18 is a right view of the gun form thereof;
FIG. 19 is a left view of the gun form thereof;
FIG. 20 is a front view in a transformed state of the gun form thereof;
FIG. 21 is a right side view in a transformed state of the gun form thereof; and,
FIG. 22 is a top view in a transformed state of the gun form thereof.

The broken lines shown in FIGS. 5, 9 and 20 illustrate features that do not form part of the claimed design.
